G. WADE.
STOPPERING DEVICE FOR BOTTLES AND THE LIKE.
APPLICATION FILED MAY 12, 1916.

1,268,899.

Patented June 11, 1918.

Inventor:

George Wade,
by *Willia Wallace White*
Atty.

UNITED STATES PATENT OFFICE.

GEORGE WADE, OF LONGPORT, ENGLAND.

STOPPERING DEVICE FOR BOTTLES AND THE LIKE.

1,268,899.

Specification of Letters Patent. Patented June 11, 1918.

Application filed May 12, 1916. Serial No. 97,196.

To all whom it may concern:

Be it known that I, GEORGE WADE, a subject of the King of Great Britain and Ireland, residing at "The Mount," Longport, 5 in the county of Stafford, England, have invented new and useful Improvements in or Relating to Stoppering Devices for Bottles and the like, of which the following is a specification.

- 10 This invention relates to stoppering devices for preventing the fraudulent refilling of bottles and the like of the type comprising a conical or inclined-walled recess or chamber wherein are arranged a valve 15 adapted to seat over the mouth of the bottle or the like or a seat provided thereat, and a ball or other stop which co-acts with said valve and the inclined surface or wall of said recess or chamber in such a manner 20 that, always seeking the lowest part of the surface or wall, it presses the valve on or against its seat even when the bottle or the like is tilted to some extent beyond the horizontal, and the bottle or the like must be 25 tilted to some considerable extent beyond the horizontal before the ball or other stop will roll away from the valve and allow the latter to leave its seat and so open the bottle or the like.
- 30 In the known stoppering devices of the particular kind specified the conical or inclined-wall recess or chamber is formed by tapered ribs on the interior of an outer casing attached to the neck or mouth of the 35 bottle or the like, or is formed in a plug or race located in either the neck of the bottle or the like or an outer casing as aforesaid, and having its depending rim or wall which incloses the recess or chamber and also the 40 valve and stop, cut away to form passages for the egress of liquid and ingress of air during pouring, and supporting legs.

The object of the present invention is to insure a more ready and effectual operation 45 of the stop to close the valve on or against its seat in the event of an attempt being made to refill the bottle or the like when tilted to or slightly beyond the horizontal.

According to this invention I combine 50 with the valve-operating ball or other stop aforesaid a second stop or member arranged in a separate recess or chamber communicating with the conical or inclined-walled recess or chamber by means of an aperture

or passage through which said second stop 55 or member is adapted to co-act with the valve-operating ball or other stop and cause it to act on and close the valve, or quicken such operation.

I will fully describe my invention with 60 reference to the accompanying drawing wherein Figure 1 is a central vertical section of one form of stoppering device embodying my improvements fitted in position. Fig. 2 is an underside plan of the 65 outer casing and Fig. 3 a section of the harbor or race hereinafter more particularly referred to. Figs. 4 and 5 are similar views to Fig. 1 showing the bottle tilted considerably beyond the horizontal for 70 pouring the contents and slightly beyond the horizontal respectively. Fig. 6 is a like view to Fig. 1 illustrating a modified arrangement.

Referring first to Figs. 1 to 5 of the drawing the stoppering device illustrated comprises, as hitherto, an outer casing *a* provided with a pouring aperture *b* and secured to the neck of the bottle *c* by a metallic capsule *d* and containing a harbor or 80 race *e* provided with a conical recess *f* in which are arranged a disk valve *g* adapted to close against a seat *h* at or in the mouth of the bottle neck, and a stop *j*. The stop *j* is preferably of frusto-conical shape or 85 form and its base and top may be flat or plain as shown, or convex or spherical. The periphery of the face of the disk valve *g* remote from the seat *h* is preferably rounded or beveled as at *k*. The depending 90 rim or wall of the harbor or race *e* which incloses the conical recess *f* is cut away to provide passages *m* for the egress of the liquid and the ingress of air to displace the same during pouring, and supporting legs 95 *n* which may be provided with feet *o* to engage recesses or an annular groove or recess *p* in the wall of the outer casing *a*.

Instead of, however, the top or upper end of the harbor or race *e* being closed as hitherto, I provide thereat a chamber *r* which communicates by means of an aperture *q* with the conical recess *f*. The apex of the stop *j* is adapted to project through the aperture *q* into the chamber *r* in which I arrange a second stop *s* adapted to co-act with the stop *j* as hereinafter explained. This second stop *s* is preferably in the form of

part of a solid or hollow sphere arranged with its convex surface toward the aperture *q* or is otherwise weighted so that it falls or tends to fall toward the aperture until 5 the bottle has been tilted to some considerable extent beyond the horizontal.

Around the inner end of the pouring aperture *b* of the outer casing *a* I provide radial ribs *t* against which the top or upper 10 end of the harbor or race *e* bears and which constitute between them radial liquid egress and air ingress passages.

When the bottle is filled in the first instance and the stoppering device fitted by 15 spinning the capsule *d* on the neck in the usual way, the pouring aperture *b* is closed by a cork (not shown) the inner end of which preferably bears on the stop *s* which in turn bears on the stop *j* and causes 20 the latter to press the valve *g* tightly on its seat *h* thus preventing any of the contents from entering the casing *a* during handling of the bottle, storage or transit, and coming 25 into contact with the cork and becoming "corky."

Decanting of the liquid is effected by tilting the bottle to some considerable extent beyond the horizontal as shown in Fig. 4. When the bottle is so tilted the stop *s* falls 30 away from the passage *q* against the radial ribs *t* aforesaid, and permits the conical stop *j* in the conical recess *f* to fall forward away from the valve *g* so that its apex projects through said passage *q*, thus allowing 35 the valve *g* to tilt or fall from its seat *h* to open the bottle and enable the contents to escape of the passages *m* in the rim or wall of the harbor or race *e*, the usual annular space *u* between the latter and the outer casing *a*, the radial passages between the ribs *t* 40 and the pouring outlet *b*.

If, while the bottle is held in the pouring position, an attempt be made to refill it, the entering liquid acting on the stop *s* will 45 raise the same or cause it to seat against the passage *q* in the top of the harbor or race *e* and operate the stop *j* in the conical recess *f* therein to close the valve *g* and prevent the liquid entering the bottle. Further, in such 50 a position the air confined in the bottle cannot escape and if liquid be introduced so gently that it does not raise or move the stop *s* only a very small quantity could be got into the bottle and, therefore, the bottle 55 is, for practical purposes, non-refillable.

An attempt to refill the bottle in any other position than tilted to some considerable extent beyond the horizontal, say when held horizontal or tilted to some extent beyond 60 the horizontal as shown in Fig. 5, would be rendered futile by the closing of the valve *g* against its seat *h* by the stop *j* sliding down the inclined surface of the recess *f* in the harbor or race *e*. In such attempts the stop 65 *s* will immediately fall toward the passage

q and act on the apex of the stop *j* projecting therethrough to overcome inertia and set the stop *j* in action. The stop *s* thus quickens the action of the stop *j* and renders it more sensitive.

70

In addition to serving as a means for insuring the action of the stop *j* the stop *s* also closes the passage *q* when an attempt is made to refill the bottle, and acts as a baffle to prevent manipulation of the valve *g* and its co-acting stop *j* by means of a wire passed through the pouring aperture *b* in the outer casing *a*.

75

I wish it to be understood that I do not limit myself to the particular forms of the stops *j* and *s*, nor to the particular formation of the conical or inclined-walled recess or chamber *f* above described, as said stops and recess or chamber may be of any other suitable forms and formations. For example, the recess or chamber *f* together with the passages *m*, aperture *q* and chamber *r* may be formed by a tapered surface provided with passages, or by tapered ribs on the interior of the body of the outer casing *a* and, in some cases, an apertured partition or the like.

80

In the modified arrangement illustrated in Fig. 6 the outer casing *a* aforesaid is dispensed with and the harbor or race *e*, valve *g*, seat *h* and stops *j* and *s* are arranged inside the neck of the bottle the mouth of which is fitted with a retaining cap *a'* secured by a capsule *d* and provided with a pouring aperture *b* and radial ribs *t* around 100 the inner end of the latter. The seat *h* rests on an annular ledge or shoulder *u* and is packed by a cork or other washer *x*.

90

The outer casing *a*, or cap *a'*, and the harbor or race *e*, valve *g*, seat *h*, and stops *j* and *s*, are preferably made of porcelain or the like, but may be of any other suitable material.

95

The outer casing and seat *h* may be connected together so that the stoppering device 110 is self-contained. When of porcelain or the like they may be connected by coating their contacting surfaces with glaze or other suitable cement and then firing. When the parts are made of other material they may be connected in any other suitable way. The spigot portion of the seat *h* (Figs. 1, 4 and 5) may be provided with a cork sleeve or washer to make a tight joint around the inside of or within the neck of the bottle similarly to the sleeve or washer *x*, Fig. 6.

115

What I claim as my invention and desire to secure by Letters Patent is:—

1. A bottle stoppering device comprising 125 the combination of an outer casing having an upper pouring aperture and radial ribs adjacent thereto, means for securing the casing to a bottle, a valve seat disposed adjacent the bottom of the casing, a valve cage disposed in the outer casing between the pour-

130

ing aperture and the valve seat and provided with an upper chamber and a lower conical chamber, said chambers communicating with each other, a hemispherical stop disposed in the upper chamber, a conical stop disposed in the lower chamber and arranged to project into the upper chamber and abut the hemispherical stop when the device is inverted, and a valve disposed between the 10 valve seat and the conical stop.

2. A bottle stoppering device comprising the combination of an outer casing having an upper pouring aperture and radial ribs adjacent thereto, means for securing the 15 casing to a bottle, a valve seat disposed adjacent the bottom of the casing, a valve cage disposed in the outer casing between the pouring aperture and the valve seat and provided with an upper chamber and a lower 20 conical chamber, said chambers communicating with each other, a hemispherical stop disposed in the upper chamber, a conical stop disposed in the lower chamber and arranged to project into the upper chamber 25 and abut the hemispherical stop when the

device is inverted and being provided with a rounded lower end.

3. A bottle stoppering device comprising the combination of an apertured pouring element provided with radial ribs, a valve 30 cage disposed below the pouring element and provided with an upper chamber and a conical lower chamber communicating with each other, a rounded stop disposed in the upper chamber, a conical stop arranged in the 35 lower chamber and adapted to project into the upper chamber and abut the first named stop, a valve disposed in the lower chamber beneath the conical stop, a valve seat disposed beneath the valve, and means for securing the pouring element in the neck of a bottle.

In testimony whereof I have signed my name to this specification in the presence of two subscribing witnesses.

GEORGE WADE.
